UNITED STATES PATENT OFFICE

THOMAS W. BRAZELL, OF PRINGLE, SOUTH DAKOTA

GATE-OPERATING MECHANISM

Application filed March 17, 1928. Serial No. 262,349.

This invention relates to mechanism for operating gates at railway grade crossings, and aims to provide means for utilizing the energy of a moving railway vehicle for closing or opening gates or other obstructions on the highway at both sides of the crossings.

An object of the invention is to provide effective means for utilizing the energy of the railway vehicle to close and open these gates, the operation of the gates being timed in accordance with the movement of the vehicle and being effected without impact or destructive effect on the gates.

Further objects of the invention will appear from the following description, taken in connection with the appended drawings, in which:

Fig. 1 is an elevation of a device embodying the invention.

Fig. 2 is another elevation of the same as viewed from the left of Fig. 1, and

Fig. 3 is a sectional detail showing the apparatus at a different stage of the operation.

Referring more particularly to the drawings, the gate operating mechanism is mounted alongside of a railway track 8, and comprises a base 10 carrying uprights 11 in which is journaled a shaft 12 carrying a large drum 13. A heavy weight or hammer 14 has two arms 15 which extend on opposite sides of the drum 13 and are pivoted to shaft 12. The upward pivoting movement of the hammer is limited by a stop 16 which is located adjacent the top of the drum and supported by suitable frame members 17 and 18. The rotation of drum 13 in the counterclockwise direction is limited by a projection 7 on the drum which engages a detent 9 fixed to the stop 16.

An actuating lever 20 is pivoted at 21, and has one of its ends extending beneath the hammer when the latter is in its lowermost position, and its other end 22 extending between two vertical guides 23 to a point near one of the rails of track 8. End 22 is rounded as shown and is adapted to be depressed by a roller 24 carried by an attachment 25 on the locomotive or other railway vehicle.

Hammer 14 is provided on its inner face

with a recess 26 in which is mounted a leaf spring 27 having its upper end bent inwardly to form a hook 28, and the periphery of drum 13 is provided with a notch 30 adapted to receive the hook. A fixed releasing member 31 is positioned adjacent the lowermost position of hammer 14 and is adapted to move spring 27 out of engagement with notch 30 as the hammer moves downwardly.

A flexible cable 32 is secured to the periphery of the disk at 33 and extends under a pulley 34 to the gates, (not shown) which are to be operated. The gates are preferably several hundred feet distant from the above described mechanism, and are adapted to be operated by a pull on the cable. Any suitable type of gate may be used, but I prefer to use the gate shown in my copending application, Serial Number 278,820, filed May 18, 1928, for railway gate and control therefor.

The operation is as follows, the parts being in the positions shown by full lines in Fig. 1. The vehicle passing over track 8 depresses, by means of its roller 24, end 22 of lever 20. The opposite end of the lever is rapidly raised, imparting a blow to hammer 14 of sufficient force to raise it to the position indicated at 14' in Fig. 1, the hammer pivoting about shaft 12 until it strikes stop 16, which arrests its movement. During this operation, hook 28 slides over the periphery of drum 13 until it reaches notch 30, when it engages therein, holding the hammer fixed relative to the drum. The weight of the hammer then causes it to return slowly to its original position, rotating the drum as it does so and winding cable 32 thereon so as to raise or lower the gates at the grade crossing. As the hammer approaches its lowermost position, member 31 engages spring 27 and moves it outwardly out of engagement with notch 30, so that drum 13 is ready to be moved back into position by a pull on the cable. Such pull will normally be produced by a similar gate operating mechanism positioned adjacent the track at some distance beyond the highway at which the gates are located, and operated in the same manner after the train has crossed the crossing.

Having described my invention what I

claim as new and desire to secure by Letters Patent of the United States is:

1. A gate operating mechanism comprising an actuating member adapted to be carried by a railway vehicle, a pivoted member adapted to be engaged and quickly moved by said actuating member, means for storing the energy imparted by said actuating member to said pivoted member, and means for utilizing said energy to close a gate.

2. A gate operating mechanism comprising a member extending adjacent a railway track and adapted to be quickly moved by a railway vehicle, means for converting the kinetic energy imparted by said vehicle to said member into potential energy and means for utilizing the said potential energy for closing a gate.

3. A gate operating mechanism comprising a member extending adjacent a railway track and adapted to be moved by a railway vehicle, a weight adapted to be raised by movement of said member, a disk adapted to be rotated by the lowering of said weight, and a cable secured to said disk and adapted to be wound thereon.

4. A gate operating mechanism comprising a cable adapted to operate a gate, a drum to which said cable is attached to be wound thereon, a weight having a detachable connection with said drum, a pivoted member having one of its ends adapted to raise said weight and having the other of its ends disposed adjacent the railway track, and an actuating member carried by a vehicle on said track and adapted to actuate said pivoted member.

5. A gate operating mechanism comprising a member pivoted adjacent a railway track, said member being adapted to be moved by a railway vehicle, a weight adapted to be struck by said member and raised by the impact thereof, and means whereby the downward movement of said weight operates a gate.

6. A gate operating mechanism comprising a member adjacent a railway track adapted to be quickly moved by a railway vehicle moving in either direction, means for converting the kinetic energy imparted by said vehicle to said member into potential energy and means for utilizing the said potential energy for operating a gate.

7. A gate operating mechanism comprising an actuating member adapted to be carried by a railway vehicle, a pivoted member adapted to be engaged and quickly moved by said actuating member on a railway vehicle moving in either direction, means for storing the energy imparted by said actuating member to said pivoted member, and means for utilizing said energy to operate a gate.

8. A gate operating mechanism comprising a weight, means whereby the passage of a railway vehicle raises said weight, and means

whereby the downward movement of said weight operates a gate.

9. A gate operating mechanism comprising a pivoted weight, a pivoted member adapted to engage said weight, an actuating member on a railway vehicle adapted to strike said pivoted member to raise said weight, and means whereby the downward movement of said weight operates a gate.

10. A gate operating mechanism comprising a pivoted weight adapted to be raised by a railway vehicle, means concentric with said weight for operating a gate, and a one way connection between said weight and said means.

11. A gate operating mechanism comprising means for storing the energy imparted to said mechanism by a railway vehicle, said mechanism being ineffective to operate said gate during the operation of said means, and means for utilizing said energy to operate a gate.
